(57) **CLAIM**

The ornamental design for a cup as shown and described.

DESCRIPTION

FIG. 1 is a bottom perspective view of a cup showing my design;

FIG. 2 is a bottom view thereof;

FIG. 3 is a front perspective view thereof;

FIG. 4 is a front view thereof;

FIG. 5 is a left view thereof;

FIG. 6 is a rear view thereof;

FIG. 7 is a right view thereof; and,

FIG. 8 is a top view thereof.

The broken lines in the figures show portions of the cup which form no part of the claimed design.
